UNITED STATES PATENT OFFICE

130,334

DESIGN FOR A HAND HELD TRAFFIC SIGNAL

Oliver R. Bryant, Minneapolis, Minn.

Application May 19, 1941, Serial No. 101,004

Term of patent 3½ years

To all whom it may concern:

Be it known that I, Oliver R. Bryant, a citizen of the United States, residing at Minneapolis, in the county of Hennepin and State of Minnesota, have invented a new, original, and ornamental Design for a Hand Held Traffic Signal, of which the following is a specification, reference being had to the accompanying drawing, forming part thereof.

Referring to the drawing:

Fig. 1 is a perspective view, looking at one face,

of the hand held traffic signal, showing my new design;

Fig. 2 is a perspective view, looking at the opposite face, of the same; and

Fig. 3 is a section taken on the line 3—3 of Fig. 1, some parts being broken away.

I claim:

The ornamental design for a hand held traffic signal, as shown.

OLIVER R. BRYANT.
